UNITED STATES PATENT OFFICE.

HARLEY W. GUTHRIE, OF ELMORE, OHIO.

CIRCUIT-CLOSING MEANS FOR FIRE-ALARMS.

1,242,178.

Specification of Letters Patent.

Patented Oct. 9, 1917.

Application filed June 24, 1916. Serial No. 105,675.

To all whom it may concern:

Be it known that I, HARLEY W. GUTHRIE, a citizen of the United States, residing at Elmore, in the county of Ottawa and State of Ohio, have invented a new and useful Circuit-Closing Means for Fire-Alarms, of which the following is a specification.

The present invention appertains to alarm apparatus, and aims to provide a novel and improved circuit closing means for an electrical alarm apparatus for dwellings, offices, banks, and other buildings, whereby if the building catches fire, the apparatus is operable for producing a prolonged or continuous operation of the bell or other signal.

It is also the object of the invention to provide an alarm apparatus having the characteristics above noted and which is exceedingly simple and inexpensive in construction, which can be readily installed in various buildings, and which will serve its office in a thoroughly practical and reliable manner.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawings, wherein:—

Figure 1 is a perspective view of a portion of a room illustrating the apparatus applied, said apparatus being illustrated diagrammatically in said figure.

Fig. 2 is a diagrammatical view of the wiring of the apparatus.

Fig. 3 is a diagrammatical view of a modification.

Fig. 4 is a perspective view of a portion of the main and secondary conductors showing how they are assembled.

In carrying out the invention, there is provided a pair of insulated main conductors 1 of sufficiently large gage to properly carry the current, and said conductors are

preferably inter-twisted in the manner of an ordinary electrical cord. The conductors 1 can be covered by any suitable heavy insulation, whereby to prevent short circuits occurring at any point between the ends of said conductors. These conductors can be extended along or behind the mop boards, picture molding, window and door casings or frames, or the like, so as to be concealed from view, and said conductors can be extended to various parts of the building where fires are apt to occur. Certain terminals of the conductors 1 are disconnected and spaced apart while the other terminals are connected in series with an electric bell or other signal 2, a battery 3 and a controlling switch 4, whereby when the circuit is closed between the conductors 1, the switch 4 being closed during working conditions, the bell or signal 2 will be operated by current supplied by the battery 3. If desired branch conductors or leaders 5 can be connected to the conductors 1, and normally open switches 6 are associated with the terminals of the conductors 5 and are applied to the windows, doors, and other barriers of the building which are liable to be opened by burglars or trespassers during the night time, although the apparatus can be used for giving a signal should a certain window or door be opened at any time whatever. As illustrated, one switch 6 is applied to the window W, and another switch 6 is applied to a door D, and said switches are so constructed, that when the window or door is opened, the circuit is closed momentarily to give a short signal, which will indicate that the window or door has been opened, and this enables an investigation to be made. The switches 6 are arranged in parallel, whereby when any switch is closed, it will connect the respective conductors 5 which in being attached to the opposite conductors 1 will close the circuit through the bell and battery. The conductors 5 can be tapped in on the conductors 1 at various points of said main conductors.

A cardinal feature of the invention resides in the combination with the main conductors 1 of secondary or auxiliary conductors 7 for purpose of fire protection. The

conductors 7 are constructed of wire of fine gage, preferably of copper, and are provided with thin insulation of silk or equivalent combustible material, while the secondary conductors themselves are fusible in the presence of flames, while the main conductors 1 are not. The secondary conductors are extended parallel with one another longitudinally side by side along and contiguous to the main conductors 1 where fire is liable to occur, and said conductors 7 are attached at intervals with the main conductors 1, as seen in Fig. 2, whereby the conductors 7 are parallel with the main conductors and provide series of shunts for the main conductors. The conductors 7 are disposed contiguous to one another and are preferably wrapped around the conductors 1, as seen in Fig. 4. Should a fire occur near the quadruple-wire cord, the insulation of conductors 7 will be burned off and said conductors will be fused together or brought in contact, thereby providing a bridge between the main conductors 1, for closing the alarm circuit. The conductors 7 need not be of large gage, and due to the short spans or shunts formed by the conductors 7, it will be noted that the circuit when closed in case of fire includes but a short length of the conductors 7. The spans or shunts are of short length, due to the fact that the conductors 7 are secured to the main conductors 1 at intervals, whereby when the conductors 7 are fused at any point thereof, the current need only traverse a short length of the conductors 7, following the course of least resistance. When the circuit is closed between the conductors 7, the circuit will remain closed until opened manually, and this will provide for a prolonged or continued signal, giving a warning of fire.

From the foregoing, taken in connection with the drawings, it will be obvious that by the connection of the conductors 5 and 7 with the main conductors 1, the apparatus is rendered particularly effective for providing a signal when the switches 6 are closed, and a continued signal in case of fire, using the same conductors 1 as the main part of the circuit in both cases. The conductors 7 need not be co-extensive in length with the conductors 1, but can be provided at such points only as desired, where there is a possibility that a fire may occur if at all.

55 In the modification illustrated in Fig. 3, an additional main conductor 1' is used in conjunction with the conductors 1, whereby the switches 6 are rendered inoperative during the day time or at such times when a burglar alarm is not wanted or desirable. The bell 2, battery 3 and switch 4 are connected in series with the conductors 1 as above described, and the conductor 1' is connected in series with the bell 2, battery

3 and one conductor 1, said conductor 1' being provided with a secondary switch 4' which can be opened when a burglar alarm is not desired. The conductors 5 are connected to the conductor 1' and that conductor 1 with which the conductor 1', bell 2 and battery 3 are connected in circuit. Thus, in case of fire, the conductors 7 being fused and connected, will close the circuit between the conductors 1, whereas if a switch 6 is closed, the alarm circuit is closed between the conductor 1' and the respective conductor 1. When the switch 4' is opened, it is evident that no signal will be given when any of the switches 6 is closed. With this form of the invention, it is only necessary to extend an additional main conductor along the other conductors, and to change the connection of one conductor 5 of each pair, said conductor 1' being properly connected with the bell and battery.

Having thus described the invention, what is claimed as new is:

1. Circuit closing means for fire alarm apparatus embodying a pair of adjacent main conductors insulated from each other to prevent short circuits therebetween, and fusible conductors contiguous to, extending longitudinally side by side along and connected at intervals to the main conductors and adapted to fuse together for electrically connecting the main conductors in the event of an abnormal increase in temperature.

2. Circuit closing means for fire alarm apparatus embodying a pair of adjacent main conductors insulated from each other to prevent short circuits therebetween, fusible conductors contiguous to, extending longitudinally side by side along and connected at intervals to the main conductors to provide series of short shunts for each of the main conductors, and combustible insulation separating the fusible conductors, said fusible conductors being adapted to be fused together in the event of abnormal increase in temperature for closing the circuit between the main conductors.

3. Circuit closing means for fire alarm apparatus embodying a pair of adjacent main conductors insulated from each other to prevent short circuits therebetween, and fusible conductors wrapped around the main conductors, extending longitudinally side by side thereof, and connected thereto at intervals, said fusible conductors being adapted to be fused together in the event of abnormal increase in temperature for closing the circuit between the main conductors.

4. Circuit closing means for fire alarm apparatus embodying a pair of main conductors insulated from each other to prevent short circuits therebetween, a pair of fusible conductors intertwined with the main conductors and connected thereto at intervals

to provide short shunts for the main conductors, and combustible insulation separating the fusible conductors, the fusible conductors being adapted to be fused together by abnormal increase in temperature for electrically connecting the main conductors.

In testimony that I claim the foregoing as my own, I have hereto affixed my signature in the presence of two witnesses.

HARLEY W. GUTHRIE.
